UNITED STATES PATENT OFFICE.

CHARLES F. UECKE, OF NEW LONDON, WISCONSIN.

BALING-MACHINE.

1,088,487.

Specification of Letters Patent. Patented Feb. 24, 1914.

Application filed August 8, 1913. Serial No. 783,712.

To all whom it may concern:

Be it known that I, CHARLES F. UECKE, a citizen of the United States, and a resident of New London, in the county of Outagamie and State of Wisconsin, have invented a new and useful Improvement in Baling-Machines, of which the following is a specification.

My invention is an improvement in baling machines, and has for its object to provide a machine of the character specified, for compressing any desired material, as for instance, cotton, hay or the like, wherein a pressing chamber is provided, and a plunger movable in the pressing chamber, together with means for permitting the plunger to be moved manually.

In the drawings:—Figure 1 is a front view of the improved baling machine, Fig. 2 is a top plan view, and Fig. 3 is a section on the line 3—3 of Fig. 2.

The present embodiment of the invention comprises a pressing or baling chamber 1, the opposite faces of the said chamber being open, and doors 2 and 3 are provided, for closing the said openings. The doors are hinged to opposite side walls of the chamber, as indicated at 4 and 5 respectively, and a plurality of latches 6 is provided for locking each of the doors in closed position. The chamber is supported on a suitable base to be presently described, and the side walls of the pressing or baling chamber are provided with longitudinal slots or passages 7, and a plunger 8 is arranged within the chamber for compressing the material to be baled. The chamber is arranged in vertical position, and the plunger 8 is normally at the bottom of the chamber. A cross bar 9 is arranged transversely of the plunger on the under face thereof, and the ends of the cross bar extend through the slots or passages 7 before mentioned.

Spaced pairs of standards 10 and 10^a are arranged at the sides of the pressing chamber and in spaced relation, the planes of the said pairs of standards being parallel with the side walls of the pressing chamber. The standards are connected at suitable points by means of cross bars 11, and the standards 10 are connected to the pressing chamber by bars 12. Bearing supports 13 are arranged at the bottom of the pairs of standards, and between the same and the baling chamber, and stub shafts 14 are jour-

naled on the bearing supports. Grooved wheels 15 are secured to the stub shafts, and a grooved wheel 16 is arranged directly above the wheel 15, adjacent to the standards 10. The said wheel 16 is secured to a 60 stub shaft 17 journaled in bearings 18 on the bars 12, before mentioned.

A shaft 19 is journaled in bearings 20 and 21, the bearing 20 being supported by a block 22 on the adjacent face of the pressing chamber and the bearing 21 being supported by one of the cross bars 11, which connects the standards 10^a. A second shaft 23 is journaled below the shaft 19 in front thereof, the said shaft being supported by bearings 24 on the pressing chamber wall, and bearings 25 on one of the standards 10^a. A gear wheel 26 is secured to the outer end of the shaft 19, and a pinion 27 is secured to the outer end of the shaft 23, the said pinion 75 meshing with the gear wheel 26. A crank 28 is also secured to the shaft 23 outside the pinion.

Chains 29 and 30 are connected with the respective ends of the cross bar 9 on the 80 plunger, and the chain 29 passes upwardly over the wheel 16, downwardly under the wheel 15, adjacent to the standards 10, beneath the pressing chamber, and under the wheel 15 adjacent to the standards 10^a and 85 thence upwardly over the shaft 19 to a connection therewith. The said chain passes over the shaft from the rear toward the front, and is secured to a lug 33, the said lug being secured rigidly to the shaft. The 90 chain 30 passes upwardly from its connection with the cross bar, over the shaft 19 from the rear toward the front, to a connection with the same lug 33.

The standards 10^a are braced against the 95 pressing chamber by metal braces 34, and the standards 10 are braced against the pressing chamber by inclined metal braces 35, the said braces inclining downward toward the pressing chamber.

The pressing chamber is connected with the centers of longitudinal bars 36, and the standards 10 and 10^a are supported on the ends of the bars. The bearing supports 13 are also supported by the bars 36 and by the standards 10 and 10^a. The pressing chamber is braced at its lower end against the base by means of inclined metal braces 37. A door 38 is also provided for the top of the pressing chamber, the door being hinged at 110

39 to that side of the chamber adjacent to the shaft 17 and latches 40 are provided for holding the door 38 in closed position.

In operation, the material to be compressed is fed into the pressing chamber with the doors 2 and 3 closed, the said material being fed through the door 38. After a sufficient amount of material has been inserted, the plunger is operated to compress the said material. The passages or slots 7 engaged by the ends of the cross bar 8 are normally closed by slides 41. The said slides are arranged at opposite sides of the chamber, each in the adjacent slot, and the lower ends of the slides are secured to the cross bar as indicated at 42.

Shafts 43 are journaled transversely of the slots or passages 7 on the outer faces of the pressing chamber in bearing blocks 44, and guide wheels 45 are secured to the ends of the shaft. The said guide wheels bear against the slides 41, to prevent displacement thereof and to lessen friction. The plunger is operated through the crank 28, and the power may be varied by varying the relative size of the gear wheel 26 and the pinion 27.

When the shaft 23 is rotated by means of the crank, the shaft 19 will be rotated at a greatly lessened speed but with greatly increased power, and the chains 29 and 30 will be wound on the said shaft. As the chains are wound on the shaft, the plunger will be lifted, and the slides will move upward with the plunger. The door 38 is notched or recessed as indicated at 46, to permit the passage of the slides when the door is closed.

The wheels 45 bear against reinforcing plates 47 on the slides. The said plates are secured to the outer faces of the slides in any suitable manner, and the lower ends of the said plates are connected to the cross bar, the said connection serving to connect the slides to the plunger.

It will be noted that the slides 41 are of a length to engage the recesses of the door at the top when the plunger is in lowermost position. At their lower ends the slides are rigidly connected with the plunger and at their tops engage the ends of the door at the recesses to limit their inward movement. The outward movement of the slides is prevented by the wheels 45.

55 I claim:—

1. In a baling machine, comprising a vertical pressing chamber and a plunger in the chamber, of doors hinged to the chamber for closing opposite faces thereof, a door 60 at the top of the chamber for closing the

top thereof, latches for holding the doors in closed position, a cross bar connected with the plunger, the side walls of the chamber being longitudinally slotted, and the ends of the cross bar extending through the slots, a slide bar in each of the slots and connected with the cross bar and moving therewith, the door at the top of the chamber having recesses in its ends through which the slide bar extends, and means connected with the ends of the cross bar for moving the plunger.

2. A baling machine comprising a pressing chamber, a door for closing the top of the chamber and hinged to the chamber, the side walls of the chamber being slotted vertically, a plunger in the chamber, said plunger having extensions extending through the slots, moving means for the plunger connected with the extensions, and slides in the slots connected with the plunger and moving therewith, the door at the top having recesses in its ends through which the slides extend, said slides being of a length to engage the recesses when the plunger is at the bottom of the chamber, and wheels journaled on the chamber and engaging the outer faces of the slides to prevent outward movement thereof.

3. A baling machine comprising a pressing chamber, a door for closing the top of the chamber and hinged to the chamber, the side walls of the chamber being slotted vertically, a plunger in the chamber, said plunger having extensions extending through the slots, moving means for the plunger connected with the extensions, and slides in the slots connected with the plunger and moving therewith, the door at the top having recesses in its ends through which the slides extend, the slides being of a length to engage the recesses when the plunger is in its lowest position, and means on the chamber engaging the outer face of the slides to limit their movement away from the chamber.

4. A baling machine comprising a pressing chamber, a door for closing the top of the chamber and hinged to the chamber, the side walls of the chamber being slotted vertically, a plunger in the chamber, said plunger having extensions extending through the slots, moving means for the plunger connected with the extensions, and slides in the slots connected with the plunger and moving therewith, the door at the top having recesses in its ends through which the slides extend.
